PLATTER OR SIMILAR ARTICLE

Albert T. Saunders, Syracuse, N. Y., assignor to Oneida Ltd., Oneida, N. Y., a corporation of New York

Application October 13, 1953, Serial No. 27,168

Term of patent 14 years

(Cl. D44—15)

Figure 1 is a plan view of a platter or similar article showing my new design; and

The essential feature of the design is the floral decoration embossed in the border of the platter.

I claim:

The ornamental design for a platter or similar article, substantially as shown and described.
